Application December 13, 1949, Serial No. 6,583

Term of patent 3½ years

(Cl. D49—1)

To all whom it may concern:

Be it known that we, Doris A. Weston and Nat J. Newman, both citizens of the United States, residing at Larchmont, county of Westchester, State of New York, and Long Island City, county of Queens, State of New York, respectively, have invented a new, original, and ornamental Design for Drying Rack, of which the following is a specification, reference being had to the accompanying drawing, forming part thereof, wherein

Figure 1 is a top plan view of a drying rack showing our new design;

Figure 2 is a front elevational view thereof;

Figure 3 is a bottom plan view thereof;

Figure 4 is a rear elevational view thereof;

Figure 5 is an end elevational view of one end, the other end being substantially the same as the one shown.

We claim:

The ornamental design for a drying rack, as shown and described.

DORIS A. WESTON.
NAT J. NEWMAN.
